PINWHEEL REGISTER

William C. Pfeiffer, Dayton, Ohio, assignor to
The Egry Register Company, Dayton, Ohio, a
corporation of Ohio

Original application February 6, 1941, Serial No.
377,715. Divided and this application November
27, 1941, Serial No. 420,718

9 Claims. (Cl. 282—15)

This invention relates to an apparatus for feeding a plurality of paper webs through a machine which produces multiple copies of a form, the invention more particularly relates to a feeding mechanism for such a machine.

It is an object of the invention to provide a paper feeding mechanism for a multiple copy form reproducing machine, wherein a plurality of needles are successively advanced into engagement with the paper webs passing through the machine for feeding the same therethrough.

It is another object of the invention to provide a needle feeding mechanism in a paper handling machine.

It is another object of the invention to provide a needle feeding mechanism in a paper handling machine in combination with a form aligning mechanism, which form aligning mechanism functions when the needle feeding mechanism is out of engagement with the paper being fed through the machine.

It is another object of the invention to provide a needle feeding apparatus for feeding paper through a machine which is constructed and arranged as an endless belt.

It is another object of the invention to provide an endless belt type of paper feeding apparatus for moving a plurality of adjacent paper webs through a machine, and which belt is constructed and arranged to release the paper webs to permit realignment of the form faces printed upon the webs.

It is another object of the invention to provide an endless belt type feeding apparatus for moving paper through a machine which is adapted to feed the paper and to align the plurality of adjacent sheets while passing through the machine.

It is another object of the invention to provide an autographic register with a continuous belt feeding mechanism having a plurality of needles thereon for carrying adjacent paper webs through the register.

It is another object of the invention to provide an autographic register in accordance with the foregoing object wherein the endless belt is provided with means for simultaneously engaging a plurality of paper webs passing through the machine to align the form faces printed thereon.

Further objects and advantages will become apparent from the following description and from the drawing.

In the drawing:

Figure 1 is a top plan view of an autographic register.

Figure 2 is a cross-sectional view of an autographic register showing the needle feeding and web aligning mechanism of this invention.

Figure 3 is a cross-sectional view, partially in elevation, of a billing machine showing the feeding and aligning mechanism applied thereto for feeding the paper webs transversely of the machine.

The feeding and aligning mechanism of this invention has been particularly applied to use upon an autographic register. However, it will be understood that the mechanism is applicable to any paper handling machine wherein it is desirable to provide accurate movement of a plurality of paper webs through a machine without the necessity of placing numerous perforations in the sheets or paper webs prior to the time of their insertion in the paper feeding or handling machine. The apparatus of this invention is particularly adaptable for using the normal file holes provided in paper sheets for properly aligning the sheets when feeding the same through a paper handling machine, such as an autographic register.

The mechanism for aligning a plurality of adjacent webs is arranged to engage the paper webs when the needle feeding mechanism is out of engagement with the paper webs. By arranging the aligning means in this manner the adjacent paper webs are free to move with respect to each other so that the aligning means can shift the paper webs to bring the form faces thereof into proper register.

In Figure 1 there is shown an autographic register which is adapted to receive the feeding and aligning mechanism of this invention. The register consists of a case 10 having a pivoted cover 18. The cover 18 permits access to the interior of the register for insertion and removal of suitable paper webs having printed form faces.

The cover 18 has a writing opening 26 below which a form face 27 of a paper web is adapted to be positioned. The paper upon which the form face 27 is printed is preferably a continuous web having repeat form faces and is adapted to be fed through the register by the feeding means of this invention. An operating handle 35 extends from the case 10 of the register and is adapted to operate the feeding mechanism contained therein. A suitable stop pin 36 is mounted upon the case 10 in a manner that it can be reciprocated with respect to the case 10 to permit the operating handle 35 to move across the pin. The stop pin 36 prevents the handle 35 from making more than one revolution, and

the operation of the handle 35 is so geared to the feeding mechanism contained within the case 10 that a predetermined length of web is ejected from the register upon each rotation of the handle 35. The amount of web ejected from the register equals one form face and the used form can be removed from the web by tearing the same therefrom across the tear off edge 28.

In Figure 2 there is shown one form of a feeding and aligning mechanism for moving a plurality of adjacent paper webs through an autographic register, such as that represented in Figure 1.

The autographic register of Figure 2 consists of a case 107 having a cover 112 pivotally carried upon the case 107 by means of pivots 113 positioned on parallel opposite sides of the case 107. The lefthand edge 114 of the top cover 112 is positioned closely adjacent a closure plate 115 secured to the case 107, but spaced therefrom to provide a slot through which the paper webs can be ejected from the autographic register. A writing opening 26a is provided in the top cover 112 and is positioned above a writing table 108 positioned below the top cover 112 and secured to the case 107 by suitable brackets 115.

The case 107 has a compartment 179 to receive a pack of prefolded and adjacently positioned webs which have been printed with suitable forms upon their faces. A compartment 177 receives one of the paper webs so that a copy of each of the forms used is retained in the autographic register.

The prefolded pack of webs, as shown in Figure 2, consists of 3 continuous webs, 109, 110 and 111. These webs have perforated file holes provided along one of the edges thereof and these file holes are used to bring the form faces on these webs into exact register when the same are being fed through the machine.

The feeding and aligning mechanisms consists of a pair of pulley wheels 100 and 101 carried upon parallel shafts 102 and 103 respectively. A continuous belt 104 extends between the pulley wheels 100 and 101. The belt 104 carries needles 105 and an aligning pin 106. The feeding and aligning mechanism is suitably carried within a case 107 in which the shafts 102 and 103 are mounted. The writing table 108 is positioned adjacent the under side of the belt 104, the belt 104 being arranged to ride across the top of the writing table 108 to carry the paper webs 109, 110 and 111 across the same.

The pulley wheel 100 is suitably driven to cause a single rotation of the belt 104 whereby the paper webs are advanced through the machine to eject a determined length thereof. The needles 105 engage and pierce the webs 109, 110 and 111 after passing over the pulley wheel 101 to draw the webs through the machine.

As will be noted in Figure 2 the aligning pin 106 is provided in a portion of the belt 104 which does not carry needles 105. The webs 109, 110 and 111 have the holes in the edges thereof at spaced intervals which are adapted to be engaged by the aligning pin 106.

The holes in the edge of the webs are perforated in the webs at the time of manufacture and are so arranged that when the printed form faces upon the webs are in proper register the holes in adjacent webs will be in exact register so that the file holes so provided can be used for the purpose of aligning adjacent form faces.

To provide carbon sheets between the adjacent paper webs 109, 110 and 111 rolls of carbon

paper 116 are positioned with respect to the webs 109, 110 and 111 that the sheets will interleave between the webs, the carbon sheets or webs passing longitudinally through the machine with the paper webs. The rolls of carbon paper 116 are adapted to be frictionally secured to prevent normal rotation thereof when the paper webs 109, 110 and 111 are fed through the machine, the paper webs sliding across the carbon webs so that the carbon can be used for a plurality of copies. When the carbon becomes worn added friction may be applied between the adjacent paper webs by the operator placing his hand upon the surface of the webs to forcibly engage the same with the writing table 108, whereby the added friction will overcome the friction preventing the carbon rolls from rotating. In this manner fresh carbon can be advanced through the machine with the ejection of a unit length of paper web.

The bottom or last copy of the web pack, namely, the paper web 109 is retained within the casing 107 to preserve a copy of form used from the webs 110 111.

After a form has been filled in upon the top web 111 it is then desired to move or feed the paper webs 109, 110 and 111 through the machine to advance the next form face beneath the writing opening 26a. As shown in Figure 2, the feeding and aligning mechanism of the invention is in a position wherein the aligning pin 106 is in engagement with the file holes provided in the edge of the paper webs 109, 110 and 111. The feeding needles 105 secured to the belt 104 are not at this time in engagement with the paper webs. Therefore, the aligning pin 106 can shift the webs 109, 110 and 111 with respect to one another to bring their form faces into proper register. When the pulley wheels 100 and 101 are rotated the aligning pin will be moved toward the left, as viewed in Figure 2, and the needles 105 will be moved to the right. The needles will thus engage the paper webs 109, 110 and 111 in a manner to pierce the same for feeding the webs through the autographic register.

In Figure 3 there is shown the feeding and aligning mechanism of Figure 2 as applied to a transverse feed of the paper webs within a billing machine. In this arrangement the typewriter 120 is suitably carried upon the rods 121 and the rollers 122 for transverse and longitudinal movement across the platen 123. A compartment 124 is provided for storage of a pre-folded web pack 125.

The feeding and aligning mechanism of this arrangement consists of pulley wheels 126 over which the belt 127 is adapted to extend. The belt 127 is provided with a plurality of needles 128 over a portion of the belt surface while the aligning pin 129 is carried within a free area 130 of the belt 127.

The web pack 125 is threaded through a feed slot 131 in the platen 123, and extends transversely across the platen into adjacent relation with the feeding and aligning mechanism. Guide plates 132 retain the web pack 125 in adjacent relation with the belt 127 in order to permit the needles 128 to pierce the web pack 125 for advancing the same transversely of the machine. The pulley wheels 126 are carried upon the shafts 133 being connected with a driving mechanism for causing an increment advance of the paper 125 through the machine.

The paper web 125 is provided with holes in the edges thereof at spaced intervals into which

the aligning pin 125 is adapted to extend when in adjacent relation with the web pack 125 to bring adjacent webs of the web pack 125 into proper register as heretofore described with regard to Figure 2.

The web pack heretofore referred to is of a type which consists of a plurality of webs loosely positioned adjacent each other. The individual webs forming the web pack can be fed to the machine as individual webs and collated in the machine, or can be arranged in a pre-folded pack. In either instance the feeding and aligning mechanism heretofore described is arranged to feed a definite increment of the web pack through the machine without requiring the necessity of any adherence between the adjacent webs. The aligning mechanism is arranged with respect to the feeding mechanism to correct any incorrect registry of adjacent webs brought about by shifting thereof while being fed by the feeding mechanism. Where individual webs, either fed individually into a machine or in a pre-folded pack form, are fed by a needle feeding mechanism there is a certain amount of slippage between the webs which requires correction at the end of each feeding operation. The mechanism of this invention thus releases the web pack from the needle feeding mechanism at the end of each feeding operation to permit an aligning pin to engage the web pack and correct the registry of adjacent form faces. It will thus be seen that the invention is not confined to a particular type of web pack but is applicable to any web pack wherein the individual adjacent webs are loosely positioned and are without adhesive means therebetween.

This application is a division of my copending application, Serial No. 377,715, filed February 6, 1941, now Patent No. 2,305,988, dated Dec. 22, 1942.

Having thus fully described my invention what I claim as new and desire to secure by Letters Patent is:

1. A machine for producing a plurality of record forms having spaced perforations therein for aligning adjacent forms comprising a writing table, pulley means positioned adjacent opposite ends of said writing table, belt means extending between said pulley means and across said writing table, said belt means having a portion of the length thereof not substantially greater than the length of said writing table provided with a plurality of needles, the remaining portion of the belt being free of needles, an aligning pin in the needle free length of said belt and disposed to engage the holes in adjacent forms to align the same when the needle free length of the belt is adjacent the record forms, said needles being disposed upon said belt to pierce said forms to feed the same through said machine.

2. In a machine for producing multiple copies of a form from a plurality of adjacent webs having an aligning hole therein adjacent each form thereon at spaced intervals comprising, means for feeding the webs through the machine in aligned relation comprising a lineally movable feeding member having a portion of the surface thereof provided with a plurality of needles a needle free surface on said feeding member substantially equal to the lineal path of travel of said member when feeding a form through the machine, an aligning pin positioned in said free surface for engaging the aligning holes, said feeding member lineally feeding the webs by means of said needles and aligning the webs by means of said

aligning pin when said needles are released from the webs.

3. In a machine for producing a plurality of record forms upon continuous webs having periodically spaced aligning holes, a writing table, an endless belt adapted to move adjacent to said table to feed record forms thereover, a plurality of needles carried by a portion of the length of said belt for feeding a predetermined increment of length of the web across said table, said belt having a needle free length that is at least equal in length to the lineal path of the belt across said writing table.

4. An apparatus for feeding a paper web comprising a writing table, an endless belt positioned adjacent said table and movable in the direction of the length of said table, means for supporting and driving said belt, a plurality of needles carried by said belt and extending over a length thereof substantially equal to the length of the writing table, and a pin carried by said belt in that portion thereof that is needle free over a length substantially equal to the length of the lineal path of the belt across said writing table.

5. An apparatus for feeding a plurality of paper webs having periodically spaced aligning holes therein comprising a writing table, an endless belt positioned adjacent said table and movable in the direction of the length of said table, means for supporting and driving said belt, a plurality of needles carried by said belt and extending over a length thereof substantially equal to the length of the writing table, and a pin carried by said belt in that portion thereof that is needle free over a length substantially equal to the length of the lineal path of the belt across said writing table and positioned upon said belt with respect to said needles to engage a paper web immediately in advance of engagement of the web by said needles to align the webs prior to feeding thereof.

6. An apparatus for feeding and aligning a plurality of record forms comprising a table adapted to support a plurality of adjacent paper webs having the record forms printed thereon and an aligning perforation adjacent each form, an endless belt positioned adjacent the upper surface of said table, means for supporting and driving said belt, a plurality of needles carried by said belt and extending over a length thereof substantially equal to the length of the writing table for feeding a predetermined increment of length of the paper webs, and a pin carried by said belt in a portion thereof that is needle free over a length substantially equal to the length of the lineal path of the belt across said writing table for engaging the holes provided in the adjacent paper webs to shift the webs with respect to one another prior to engagement thereof by said needles and when moved by said pin.

7. An apparatus for feeding and aligning a plurality of record forms comprising a table adapted to support a plurality of adjacent paper webs having the record forms printed thereon and an aligning perforation adjacent each form, an endless belt positioned adjacent the upper surface of said table, means for supporting and driving said belt, a plurality of needles carried by said belt and extending over a length thereof substantially equal to the length of the writing table for feeding a predetermined increment of the length of paper webs, and a pin carried by said belt in a portion thereof that is needle free over a length substantially equal to the length of the lineal path of the belt across said writing table for en-

gaging the holes provided in the adjacent paper webs to shift the webs with respect to one another when moved by engagement with said pin, said needles engaging said webs subsequent to the shifting thereof by said pin and releasing the webs prior to the shifting thereof.

8. An autographic register comprising a casing, a compartment within said casing for receiving a pack of pre-folded plural copy forms having an aligning hole in each form, a writing table, means for supporting the plural webs of said pre-folded pack for directing the same in a plane of movement substantially parallel to the plane of said writing table, an endless belt positioned adjacent said table, means for supporting and driving said belt, a plurality of needles in a portion of the length of said belt for engaging the webs to move a predetermined increment thereof across said table, and a pin carried by said belt in a portion thereof that is needle free for a length that is at least equal to the length of the lineal path of the belt across the writing table for engaging said holes to shift the webs with respect to one another prior to engagement of said webs by said needles.

9. An autographic register comprising a casing, a compartment within said casing for receiving a pack of pre-folded plural copy forms having an aligning hole in each form, a writing table, means for individually supporting the plural webs of said pre-folded pack for directing the same in a plane of movement substantially parallel to the plane of said writing table, an endless belt positioned adjacent said table, means for supporting and driving said belt, a plurality of needles in a portion of the length of said belt for engaging the webs to move a predetermined increment thereof across said table, and a pin carried by said belt in a portion thereof that is needle free for a length that is at least equal to the length of the lineal path of the belt across the writing table for engaging said holes to shift the webs with respect to one another prior to engagement of the webs by said needles, said needles releasing the webs prior to engagement of said webs by the pin.
